UNITED STATES PATENT OFFICE.

CHARLES G. PETZOLD, OF PROVIDENCE, RHODE ISLAND.

LOOM-SHUTTLE.

1,036,699.

Specification of Letters Patent. Patented Aug. 27, 1912.

Application filed February 2, 1911. Serial No. 606,074.

To all whom it may concern:

Be it known that I, CHARLES G. PETZOLD, a citizen of the United States, residing at Providence, county of Providence, State of Rhode Island, have invented an Improvement in Loom-Shuttles, of which the following description, in connection with the accompanying drawing, is a specification, like letters on the drawing representing like parts.

This invention relates to shuttles for looms and has for its object to provide a novel shuttle provided with means for detecting the presence of a knot or slub in the 15 yarn and breaking the yarn if a knot is found therein so that the shuttle-changing or loom-stopping mechanism which is ordinarily brought into play upon the breaking of the yarn will operate to change the 20 filling or stop the loom as the case may be, and also to provide a simple arrangement by which the yarn will be broken, thus calling into play the loom-stopping or filling-changing mechanism whenever a float occurs 25 or whenever the shed is not properly formed so that the warp threads bind on the shuttle.

The features wherein the invention resides will be more fully hereinafter described and 30 then pointed out in the appended claims.

In the drawings wherein I have illustrated a selected embodiment of my invention which is sufficient to show the principle thereof, Figure 1 is a plan view of the 35 thread-delivery end of the shuttle showing the improvements; Fig. 2 is a section on the line $\alpha-\alpha$, Fig. 1; Fig. 3 is a side view of the slub or knot detecting plate and the float detector detached from the shuttle.

The shuttle body is shown at 1 and the 40 end of the spindle on which the yarn 3 is wound is shown at 2. The yarn is delivered from the shuttle through a shuttle eye 4 of some suitable or usual construction. These 45 elements are such as are commonly found in shuttles and form no part of the present invention.

My improvements consist of a knot or 50 slub detecting plate 5 which is set into the shuttle to extend across the bobbin-receiving chamber 6 adjacent the thread-delivery eye 4. This plate may be held in the shuttle in any suitable way and I have herein shown the edges of it as fitting in the grooves 7 55 formed in the sides of the shuttle and as held

from vertical movement by means of a cross pin 8 which extends across the shuttle and engages the lip or flange 9 at the bottom of the plate 5. This plate is provided with the narrow slot 10 through which the yarn 3 passes, said slot being of a width to freely admit the yarn provided the latter is perfectly smooth and free from knots, but being so narrow as to prevent a knot or slub from being drawn through. As a result if a knot 60 occurs in the yarn, the said knot will catch on the plate 5 and the yarn will be broken, thus calling into play the usual filling-replenishing or loom-stopping mechanism which are rendered operative whenever the 65 filling does break or becomes exhausted. I have shown the slot 10 as having a widened mouth 11 to facilitate the threading up of the shuttle. Associated with this plate 5 is a device for severing the thread whenever a 70 float occurs, or whenever the shed is not properly formed. This device comprises a lever 12 pivoted to the plate at 13 and having a yarn-severing finger 14 which overlies the 75 plate 5 and is adapted to swing across the slot 10 therein, as shown in dotted lines Fig. 2. The lever 12 is also provided with a finger 15 which extends at right angles to the plate 5 and adjacent the upper edge 16 of the shuttle body. The lever is normally 80 held in the full line position Fig. 2, by means of a spring 17 or some other suitable device, and when in this position the finger 14 is at one side of the slot 10 and the finger 15 is above the level of the top of the shuttle. 85 If during the weaving operation the shed is not properly formed so that the warp threads press on the upper side of the shuttle during its flight, the engagement of these warp threads with the arm 15 will 90 swing the latter downwardly into the dotted line position, thus moving the finger 14 across the slot 12 and thereby breaking or severing the yarn 3 as will be obvious. During 95 this operation the finger 14 and the edge of the slot 10 act somewhat as a pair of shears for cutting or breaking the yarn. As soon as the yarn is broken, the usual weft-detecting mechanism comes into play to either set in operation the filling-replenishing mechanism or loom-stopping mechanism 100 as the case may be.

It will be observed that my device is very simple and can be readily applied to any shuttle.

Various changes in the construction of the parts may be made without departing from the invention.

Having fully described my invention, 5 what I claim as new and desire to secure by Letters Patent is:—

1. In a shuttle, the combination with a shuttle body having a bobbin-receiving chamber and a delivery eye, of a plate extending transversely across the end of the bobbin-receiving chamber and provided with a slot of sufficient width to receive freely yarn which is free from knots but of insufficient width to permit knots to pass therethrough, a yarn-breaking member pivoted to said plate to swing parallel thereto, and means to actuate said member to break the yarn on the occurrence of a float. 10
2. In a shuttle, the combination with a shuttle body having a bobbin-receiving chamber and a delivery eye, of a plate extending transversely across the end of the bobbin chamber and provided with a slot through which the yarn passes, a yarn-breaking member pivoted to said plate to swing parallel thereto and having a finger extending therefrom in the direction of the length of the shuttle and occupying a position normally slightly above the side of the 15 shuttle. 20
- 25

shuttle so that if the warp threads bind on 30 the shuttle they will press said finger and swing the yarn-breaking member across the slot thereby to break the yarn.

3. In a shuttle, the combination with a shuttle body having a bobbin-receiving 35 chamber and a delivery eye, of a plate extending transversely across the end of the bobbin chamber and provided with a slot through which the yarn passes, a yarn-breaking member pivoted to said plate at the 40 upper edge thereof adjacent said slot, said member having a portion extending laterally therefrom, and a finger extending from the end of said lateral portion in the direction of the length of the shuttle and occupying 45 a position slightly above the side of the shuttle, so that if the warp threads bind on the shuttle they will press said finger outwardly and thereby swing the yarn-breaking member across the slot to break 50 the yarn.

In testimony whereof, I have signed my name to this specification, in the presence of two subscribing witnesses.

CHARLES G. PETZOLD.
